UNITED STATES PATENT OFFICE.

LOUIS E. WILLIAMS, OF FREMONT, OHIO, ASSIGNOR TO NATIONAL CARBON COMPANY,
OF CLEVELAND, OHIO, A CORPORATION OF NEW JERSEY.

APPARATUS FOR LINING DRY CELLS.

1,210,577.

Specification of Letters Patent.

Patented Jan. 2, 1917.

Application filed May 10, 1913. Serial No. 766,894.

To all whom it may concern:

Be it known that I, LOUIS E. WILLIAMS, a citizen of the United States, residing at Fremont, in the county of Sandusky and State 5 of Ohio, have invented a certain new and useful Improvement in Apparatus for Lining Dry Cells, of which the following is a full, clear, and exact description.

This invention relates to apparatus for 10 lining containers, more particularly dry cells.

The usual method of procedure in making dry cells is to insert the bibulous lining and bottom disks manually in the zinc container, 15 no machinery whatever being used.

The object of my invention is to devise a machine for accomplishing the same results rapidly and automatically.

Other objects will appear in the following 20 description.

Figure 1 is a front view of a can lining machine. Fig. 2 is a cross-sectional view of a dry cell after the lining and disks have been inserted. Fig. 3 is an end view of Fig. 25 1 taken from the left, certain parts being omitted. Fig. 4 is an isometric projection of the can feeding mechanism. Fig. 5 is a cross-sectional view on the line A—A of Fig. 1 looking toward the right, showing the driving means. Fig. 6 is a cross-sectional view 30 on the line B—B of Fig. 1 also looking toward the right, certain parts being omitted. Fig. 7 is a cross-sectional view on the line C—C of Fig. 1 looking toward the right, 35 with certain parts omitted. Fig. 8 is an enlarged partial cross-sectional view taken on the line D—D of Fig. 1. Fig. 9 is a partial cross-sectional view of the rolling mechanism for inserting the lining. Fig. 10 is a 40 side view, with parts removed, of a device used to keep the cans in alignment with the inserting apparatus. Fig. 11 is a cavalier projection of the crosshead and attached parts for inserting the lining in the cans. Fig. 12 is a plan view of the slide for inserting 45 the first disk. Fig. 13 is a plan view of the slide for inserting the last two disks.

Referring to Figs. 1 and 3, the frame of the machine may consist of a number of supporting legs 1 joined at the top by cross-pieces 2 and at the bottom by braces 3. Upon the cross pieces 2 rests a long supporting member or beam 4 extending the entire length of the apparatus. At each end of

this support, a toothed sprocket wheel 5 is 55 fastened by bearings 6. The teeth of the sprocket wheels 5 extend through a slot 7 in the ends of the support 4 and engage an endless chain or conveyer 8. To the endless chain 8 are attached in any convenient manner 60 a number of cylindrical holders 9, into which the zinc cans 10 of the dry cell are placed. These holders are arranged equidistant along the endless chain and have a height somewhat less than the height of the 65 can 10.

At the right hand side of the apparatus, as shown in Fig. 1, the upright members 11 are joined by the cross pieces 12 at the top and bottom (Fig. 5). A shaft 13 is supported in 70 bearing 14 resting on the upper cross-piece 12. Other bearings are provided at the other points along the shaft. A pulley 15 is fastened to the shaft 13 and is driven by any source of power, a belt 16 being shown. The 75 shaft 13 rotates the shaft 21 by means of gears 18, 19 and 20. A mutilated gear 22, keyed on shaft 21 meshes with the pinion 23 on the shaft 17 and thus turns it intermittently. In order to support the train of 80 gearing, a pair of uprights 24 and 25 shorter than uprights 11 may be provided. One of these is shown in Fig. 1, the other being directly behind it. The uprights are joined at the top as shown in Fig. 5 by a member 26 85 similar to cross bar 12. The idler 19 is pivoted to the member 26 while both the shafts 17 and 21 are similarly secured to the rear upright 24 on opposite sides thereof and at such a distance apart that the mutilated gear 22 and pinion 23 will mesh 90 properly.

As stated previously, the shaft 17 is rotated intermittently by means of the gear 22, and in order to prevent it from rotating 95 after the mutilated gear has ceased to act on it, due to its inertia and that of the connected parts, I use a catch shown in Figs. 5 and 10. This consists of a disk 27 fitted to the shaft 17, having a lug or shoulder 28 100 thereon. The lug 28 engages the dog 30 pivoted at 31 to a projection 33 of the leg 1. A spring 32 connected between the dog 30 and the cross piece 2 holds it against the disk. The disk 27 is placed in a position 105 such that the end 29 of the dog engages the lug 28 at the instant that the mutilated gear 22 lets go of the pinion 23. A trip 33 is se-

cured on the shaft 21 to raise the dog 30 out of engagement, just before the mutilated gear again meshes with the pinion.

The shaft 17 is supported at various points along its length by the brackets 34 which rest upon the cross-pieces 2, one being shown in Figs. 3 and 4. A plate 35 having a notch 36 is attached to the end of the shaft 17. A pin 37 secured to the plate moves in a slot 38 in the reciprocating arm 39, which is pivoted at 40 to a supporting member 41. This may be conveniently fastened to the leg 1 as shown. At the other end of the arm 39, a connecting rod 42 is attached by a double acting joint 43. A projection of the joint turns in the arm 39 and the connecting rod is pivoted between lugs on the joint so that it can swing either in the plane of the arm 39 or in a plane at right angles thereto. The other end of the connecting rod is fastened to the short link 45 by a pin 44 which is parallel to the plane of the shaft 17. The link 45 is also pivoted at the other extremity to the arm 47 by a pin 46, at right angles to the pin 44. The feeding arm 47 rotates loosely about the axis 48 and has a dog 50 adapted to engage the ratchet wheel 49 rigidly mounted on the axis 48. A suitable spring 51 is connected between the reciprocating arm 47 and the dog to keep it in engagement with the ratchet wheel 49. A pivoted arm or dog 52 operated by a spring 53 cooperates with a notch 36 of the plate 35 to prevent the shaft 17 from rebounding in the opposite direction as will be fully described later.

To the left of the driving mechanism in Fig. 1, there are successively arranged devices for, first: inserting a bottom disk; second, a cylindrical lining; and third, two additional bottom disks. These devices will now be described in the order given.

The first is best shown in Figs. 1 and 6. Referring thereto, two standards 54 of an inverted Y shape are securely fastened to the support 4 and are provided with bearings 55 for the shaft 13. The eccentric 58 consists of a circular portion 56 which is eccentrically mounted upon the shaft 13 and may be adjusted thereon by manipulating screws 57. A frame surrounds the eccentric and is made up of two semi-circular portions 58' and 59 bolted together. The lower portion 59 has a projection 60 into which a connecting rod is fastened. The connecting rod 61 is pivotally secured to a cross head 62 which moves between the guides 63 fastened to the standards 54. Attached to the head 62 is a plunger 64 which moves in a hollow guide way 65. The guide way is supported by a member 66 resting upon bar 67 and shelf 68 both being fastened across the standards. The shelf is also supported by braces 69 between it and the standards. The plunger 64 is reciprocated by the eccentric

58 on the shaft 13 and passes through the circular holes 70 in the member 66 and a corresponding hole 71' in the slide 71. A magazine 72 containing disks 73 and weight 73' is secured to the member 66. A circular opening 74 in the upper part of the member permits the bottom disk to rest on the slide. The slide 71 is fastened to the projecting lug 77 of the eccentric 78 by a connecting rod 75 pivoted at 76. This eccentric is constructed in the same manner as the eccentric 58 previously described. The eccentric 78 is rotated upon the intermittently rotating shaft 17. The stroke of the plunger 64 is sufficient to permit it to descend substantially to the bottom of the cans 10. During the period in which the shaft 17 is stationary, the single hole in the slide 71 is in alignment with the hole 70 below the plunger so as to permit it to pass therethrough, the openings in the can 10 underneath being likewise in alignment.

The mechanism for inserting the cylindrical lining is placed to the left of the first mechanism. Referring to Figs. 1 and 7, this device consists of a hollow cylindrical plunger 79 fastened to a frame 80. The frame and plunger are reciprocated by means of two eccentrics 81 and 82 similar to the eccentric 58. The frame 80 and the eccentrics are connected by means of connecting rods 83. A flared guide or funnel 84 is slidably suspended from the frame by rods 85 and is yieldingly retained against the nuts at the lower end by springs 87 surrounding the rods. The frame 80 joins two cross-heads 80', each of which moves between two guides 89 fastened to the upright members 90 as shown in Fig. 7.

The uprights 90 are connected across the top by beams 91 and at the bottom are fastened to the support 4. A shaft 92 is mounted across the beams 91 and fits in bearings thereon. A sprocket wheel 93 is secured on this shaft and is rotated by chain 94 and toothed wheel 95 on the intermittently rotating shaft 17. The bevel gear 96 on the shaft 92 meshes with the pinion 97 mounted on a vertical shaft 98. This shaft is supported by a bearing 99 fastened across the uprights 90. At the other extremity of the shaft 98 is fastened a cylinder 100 having a longitudinal slot 101 as shown in Fig. 8. A sheet metal drum or cylinder 102 having flaring ends 103 and 104 surrounds the cylinder 100, a space 105 being left between the two cylinders to receive the lining. An opening 107 is left between the ends 103 and 104 so that the lining 108 may be pushed into the slot 101 and then wound up in the intermediate space 105. The sheet metal cylinder 102 rests upon the table 106 supported by the members 90, a hole 106' being provided for the guide 84 to pass therethrough. The manner in which the

hollow cylindrical plunger 79 removes the lining and deposits it in the can will be described later.

After the lining is inserted by the plunger, 5 two more disks are put in place by a mechanism placed still farther to the left. This arrangement consists of two devices identical with that described for inserting a single disk, with the exception that one slide 116 10 removes the disks from both devices. The plungers 109 and 110 are operated by the eccentric 111 identical with 58 and are fastened to the head 112 moving between guides 113 secured to the standards 114. A connecting rod 115 joins the eccentric to the head 112. The slide 116 reciprocates in the frame 117 supported on a table 118. This slide has two holes 116' and 116'' side by side adapted to pass under the two magazines 120 and 120' (Fig. 13) and is operated by eccentric 121. The other details of this arrangement are identical with those of the disk inserting mechanism first described.

A standard 122 at the left hand extremity 25 as shown in Fig. 1 supports the end of the shaft 13. Projection 123 is attached to this standard to serve as a pivot for the catch 52. Another projection 124 on this standard serves as a fastening for the spring 53. 30 Fig. 2 shows a dry cell can with the elements which are inserted by this apparatus. In the zinc can 125 is placed a bottom disk 126, a lining 127 and disks 128 and 129 inside of the lining and on top of the bottom 35 disk.

The intermittent operation of the shaft 17 is produced as follows: Referring to Figs. 1 and 5, the driving mechanism for the apparatus is operated by a belt 16 driven by any 40 source of power. By this means a pulley 15 fastened to the shaft 13 is rotated continuously. In the section shown in Fig. 5, the direction of this rotation is indicated as being clockwise. Upon the shaft 13, the gear 18 and the four similar eccentrics 58, 81, 82 and 111 are rotated continuously. The gear 18 turns the idler 19 which meshes with another gear 20 similar to gear 18. The gear 20 and shaft 21 are therefore rotated in the 45 same direction, and with the same speed as the shaft 13. The mutilated gear 22 on the shaft 21 will also be rotated in the same manner. The mutilated gear meshes with a pinion 23 on the shaft 17. The two gears 50 have the same number of teeth but the mutilated gear is approximately three times as large as the pinion, hence, the pinion is rotated once during a complete revolution of the mutilated gear. The shaft 17 thus rotates counter clockwise and makes the same 55 number of revolutions in a given period as the shafts 13 and 21, but rotates three times as fast. It remains stationary during the other two-thirds revolution of the shafts 13 and 21.

In order to prevent the shaft from rotating after the mutilated gear has ceased to act on the pinion 23, I make use of the arrangement shown in Figs. 5 and 10. At the instant that the teeth of the mutilated gear cease to mesh with pinion 23, the catch 28 70 will engage the shoulder 29. This will prevent the inertia of the moving parts from rotating the shaft 17 any farther. The impact of the dog against the catch is liable to cause the shaft 17 to rebound and in order to prevent this, the dog 52 placed on the feeding end of the shaft, as shown in Figs. 3 and 4, drops into notch 36 of the disk 37, 75 at the same instant that the catch 28 and shoulder 29 come into engagement and the shaft is thus prevented from rotating in either direction. Spring 53 maintains the dog 52 in engagement with the periphery of the disk 35. The mutilated gear 22 and 80 shaft 21 will then continue their rotation while the shaft 17 and connected parts remain stationary. The catch 29 must, however, be lifted before the mutilated gear meshes again with the pinion. A trip 33 85 (Fig. 10) is therefore secured to the shaft 21 to lift the dog 29, just before the mutilated gear meshes with the pinion and to hold it long enough to permit the shoulder 28 to pass under the end of the dog. When 90 95 the trip 33 rotates farther, it will release the dog and permit the spring 32 to return it to its original position.

During the rotation of the shaft 17, rotary motion is transmitted to the shaft 98 100 (Fig. 7) through the sprocket 95, chain 94, sprocket 93 and bevel gears 96 and 97. The shaft 98 is turned through two complete revolutions for each revolution of the shaft 17 for a purpose that will be described later. 105 This chain and gear mechanism and the connected parts insert the lining in the can as follows: The operator will place a lining 108 in the slot 101 where it will be in position to be coiled around the former 100 as 110 soon as it commences to rotate. When it is coiled therearound, the plunger 79 descends through the action of the eccentrics 81 and 82 and forces it into the can underneath. In order to guide the lining properly, the 115 funnel 84 is provided as previously described. At a predetermined point in the upward travel of plunger 79, the nuts on the rods 85 raise the funnel 84 from engagement with the can 10, and likewise at a predetermined point on the downward stroke of the plunger, the funnel is pushed downward into engagement therewith where it remains during further descent of the plunger. As the plunger descends, the rods 85 slide 120 through the holes in the funnel and the springs 87 are compressed. In this way the funnel is retained above the cans during the period that they are moved along with conveyor 8, but is lowered into engagement with 125 130

the end of the can beneath the lining mechanism just before the lining is pushed down into it.

The complete operation of the apparatus 5 in inserting the disks and the lining is as follows: Referring to Fig. 1, the dry cell cans or containers 10 will be placed in the holders 9 at the right end of the apparatus by any means. For the purpose of explanation, it will be assumed that the cans are 10 placed manually in the holders. The rotating shaft 13 will transmit motion through the train of gears and cause the intermittent movement of shaft 17 as has been previously explained. The shaft 17 through 15 the arms and links at the left hand side of the apparatus of Fig. 1 (shown in detail in Fig. 4) will step the conveyer 8 along one notch at a time for each revolution. The 20 distance moved is the same as the distance between the centers of the can holders 9. In this way the conveyer is stepped along until the first can placed therein is adjacent the disk inserting mechanism. The next 25 revolution of the shaft 13 causes one complete revolution of the shaft 17 through the mutilated gear arrangement and this rotation moves the conveyer so as to place the can directly under the member 65 (Fig. 6) 30 where it remains stationary. During the time that the conveyer was moved through this distance, the eccentric 78 on the shaft 17 pushed the slide 71 to the right in Fig. 6 to receive a paper disk 73 in the hole 71' 35 and drew it back with this disk in alignment with the can 10 beneath. As shown in Figs. 4 and 6, the shaft 17 has turned through half a revolution, leaving one-half of a revolution yet to be completed before 40 the mutilated gear ceases to mesh with the pinion 23 thereon. The ratio of the pitch of the gears 22 and 23 is such that the plunger 64 is entirely above the slide 71 while the shaft 17 is rotating. When the shaft 45 ceases to rotate, the descending plunger pushes the paper disk from the slide 71 into the can 10 and then moves upward to clear the slide before the mutilated gear 22 again meshes with gear 23. The next engagement 50 of these two gears causes the conveyer to be stepped forward again to place another can under the disk inserting mechanism where the same process is repeated. The first can is stepped along until it reaches the mechanism 55 for inserting the lining, and during this period disks have been inserted in the succeeding cans as they pass under the disk inserting mechanism. Just before the can is moved up to the position under this mechanism, a lining 108 is shoved into the slot 101 of the former 100 in position to be coiled thereon. This lining can be placed in position by any means but it is assumed that it will be done manually by any attendant. When the mutilated gear meshes 60

with the pinion on the shaft 17 motion is transmitted to the former 100 through the chain and gears (Fig. 7) and it is turned around twice. During the revolution of the former, the lining is drawn in and wrapped 70 around it inside of the drum 105. The lining is of such a length that it will have overlapping ends when coiled on the former 100 but in order to have the slot 101 in correct position to receive another lining, it is turned 75 through two revolutions though, of course, it could equally as well be designed to turn through any whole number of revolutions greater than one. During the time that the lining has been drawn in and wrapped 80 around the former, the sleeve or plunger 79 has been entirely above it as is shown in Fig. 7. This plunger is forced downward by the eccentrics 81 and 82 (Fig. 1) and engages the coiled lining 108 after it ceases 85 to rotate and pushes it down through the funnel 84 into the can 10 on top of the paper disk. Further, rotation of the shaft 13 then causes the plunger 79 to rise and clear the cylinder 100, and when the mutilated gear 22 again comes in engagement 90 with the pinion 23, the conveyer 8 is stepped forward and the next can is placed under the lining mechanism. Just as soon as the plunger 79 clears the former 100 the operator 95 will place another lining 108 in the slot 101 in readiness to be coiled about it when the shaft 17 is again rotated.

The can first described after having the lining placed therein is stepped forward 100 repeatedly until it comes under the plunger 110, Fig. 1, in position to have a second disk inserted therein. The slide 116 (Figs. 1 and 13) is reciprocated back and forth by an eccentric on the shaft 17 exactly in the 105 same manner as the slide 71 which placed the first disk in the can. When the shaft 17, therefore, is turned through one revolution, the paper disk drops into the hole 116' in the slide 117 and is drawn to a position 110 over the can where it will be forced therein by the descending plunger 110. The can is then further stepped along until it comes under the plunger 109 in position to receive a third disk. This disk is placed in position 115 to be forced into the can by the slide 116. The disk is brought into position over the can after having been fed into the hole 116" from the magazine 120'. This is the last 120 operation that will be performed on the can traced along the container and it will be stepped along until it reaches the left hand end of the apparatus where it will either be removed by an attendant or drop into a hopper as it turns around the wheel 5.

In the way described, each can that is put in the container on the right hand side will pass successively first under the first disk inserting mechanisms to receive a disk; second, under the lining mechanism to receive 130

a lining; third, under the second disk inserting mechanism to receive a second disk; and fourth, under the third disk inserting mechanism to receive the third disk.

5 It is the usual practice to place one lining and three disks in each dry cell container but it will, of course, be obvious that my invention is not limited to this number. The apparatus can be arranged to insert

10 any number of disks or any number of linings and the example illustrated in the drawing is only intended to be illustrative of the manner in which the various operations can be performed.

15 Having described my invention, what I claim is:

1. In a can lining machine, a support for the can, a rotatable member for shaping the lining, concentric retaining means spaced 20 from the shaping member a distance approximately equal to the thickness of the lining and means reciprocating between said first mentioned means and said shaping member for forcing the shaped lining from the 25 shaper into the can.

2. In apparatus for forming sheets into tubes, a vertical cylinder having a groove, a member inclosing the cylinder having an opening and an outwardly flaring guide for 30 admitting a sheet to the groove, means for intermittently rotating the cylinder to coil a sheet thereon, and vertically reciprocating means adapted to pass between the cylinder and the inclosing member to force the tube 35 from the cylinder.

3. In a can lining machine, a horizontal conveyer for carrying cans, a vertical cylinder having a groove, a member inclosing the cylinder having an opening and an outwardly flaring guide for admitting a lining 40 to the groove, means for intermittently rotating the cylinder to coil a lining thereon, and vertically reciprocating means adapted to pass between the cylinder and the inclosing member to force the lining from the cylinder into a can.

4. In a can lining machine, a rotatable member for shaping a lining, a guide surrounding the member and adapted to be reciprocated whereby it intermittently engages the can and means for pushing the lining through the guide into the can during the period when said can and guide are in engagement.

5. In a can lining machine, a member for shaping a lining, a flared guide to direct the lining into the can, means adapted to yieldingly support said guide, a plunger for removing the lining from the shaper, and 50 means for simultaneously reciprocating the guide supports and the plunger.

6. In a can lining machine, an intermittently movable conveyer having a plurality of holders for cans, means for moving a disk adjacent a can opening, and means for forming a lining while the conveyer is mov- 65

shaped lining, a plurality of rods for slid- 70 ingly supporting said member, springs around the rods and engaging the member, a plunger for removing the lining from the shaper and means for simultaneously recip-rocating the funnel and plunger whereby the plunger engages the lining and the funnel engages the can while the conveyer is stationary.

7. In a can lining machine, a support for 75 the can, a rotatable cylinder for shaping the lining, said cylinder having a groove adapted to engage an edge of the lining and retain it while the lining is coiled thereon, a guide surrounding the cylinder and the can, 80 a plunger slidably fitted over the cylinder, means for reciprocating the plunger to push the lining off the cylinder into the can and means coöperating therewith to simultaneously lower the guide into engagement with 85 the can.

8. In a can lining machine, a plurality of loose-fitting holders for the cans, means for shaping a lining, means for conveying a plurality of cans successively adjacent the first 90 mentioned removing means, means adapted to engage the shaped lining to place it in the can, alining means adapted to engage the cans and means for simultaneously reciprocating the alining and removing means. 95

9. In a can lining machine, concentric cylinders for shaping a lining therebetween, a conveyer having holders adapted to receive the cans extending under the cylinders, means for intermittently moving the conveyer and for rotating the inner cylinder, a third cylinder reciprocating between the concentric cylinders and means for moving the conveyer on the withdrawal stroke of the cylinder. 100

10. In a can lining machine, a cylinder for shaping a lining thereon, a hollow cylinder surrounding said shaper for retaining the lining, a conveyer having a plurality of holders for retaining the cans, means for intermittently moving the conveyer adjacent said cylinders, means for pushing the shaped lining into said cans as they are moved adjacent the cylinder and means to guide the lining into the can as it is moved off the shaper. 105

11. In a can lining machine, an outer cylinder, an inner cylinder for forming a lining therebetween, a conveyer having holders adapted to receive the cans extending 120 under the cylinder, means for intermittently moving the conveyer and for rotating the inner cylinder and means for pushing the lining from between the cylinders into the can while said parts are stationary. 125

12. In a can lining machine, an intermittently movable conveyer having a plurality of holders for cans, means for moving a disk adjacent a can opening, and means for forming a lining while the conveyer is mov- 130

ing, and means for inserting said disk and linings into the cans while the conveyer is stationary.

13. In a can lining machine, a conveyer having holders adapted to receive the cans, means for intermittently moving said conveyer, means for inserting a disk in the cans and means for shaping a lining and placing it against the inner surface of the can and 10 on top of said disk and means for placing a second disk within the lining and on top of said first mentioned disk.

14. In a can lining machine, a driving means, an intermittently rotating shaft 15 driven therefrom, means to prevent kinetic rotation of said intermittently rotating shaft, an intermittently rotating shaper for the lining, a belt conveyer carrying holders spaced apart moving around two terminal 20 wheels and intermittently driven, and means for removing the lining from the shaper into the can while said conveyer and shaper are stationary.

15. A can lining machine comprising 25 mechanism to apply a bottom lining to the can, mechanism to apply a side lining to said can and means to successively operate said mechanisms.

16. A can lining machine comprising 30 mechanism to apply a bottom lining to the can, mechanism to apply a side lining to said can, means to successively operate said mechanisms and means to arrest said cans in their bottom and side lining positions, 35 and to advance them therefrom.

17. A can lining machine comprising 40 mechanism to apply a bottom lining to the can, mechanism to apply a side lining to said can, means to successively operate said mechanisms, a carrier to successively deliver the cans to the bottom and side lining mechanisms, and automatic means coöperat-

ing with said carrier to position said cans relatively to the bottom and side lining positions.

18. A can lining machine comprising mechanism to apply a bottom lining to the can, mechanism to apply a side lining to said can, means to successively operate said mechanisms, a carrier to successively deliver 50 the cans to the bottom and side lining mechanisms, a can positioning device consisting of a catch adapted to arrest the movement of said carrier and means for releasing the catch.

19. A can lining machine comprising mechanism to apply a bottom lining to the can, mechanism to apply a side lining to said can, means to successively operate said mechanisms, a carrier to successively deliver 60 cans to the bottom and side lining mechanism, an endless belt trained about pulleys and means to arrest forward movement of the belt, means to arrest rebound, and means to impart step-by-step movement to said belt.

20. A machine for side lining cans comprising means to spirally roll a lining section in a number of overlying turns, and means to insert the rolled lining into the 70 can constructed to permit the lining to expand against the side wall.

21. A can lining machine comprising 75 means to apply a bottom lining to a can and other means to spirally wind a side lining section and to insert it into the can, constructed to permit the lining to expand away therefrom against the can wall.

In testimony whereof, I hereunto affix my signature in the presence of witnesses. 80
LOUIS E. WILLIAMS.
